UNITED STATES PATENT OFFICE.

HUGO JUNKERS, OF DESSAU, GERMANY.

LIQUID HEATER.

Application filed June 29, 1920. Serial No. 392,837.

To all whom it may concern:

Be it known that I, Hugo JUNKERS, a citizen of the German Empire, residing at Dessau, Germany, have invented certain new and useful Improvements in Liquid Heaters, of which the following is a specification.

My invention relates to appliances in which combustion gases are led along cooled metal partitions such as heaters for liquids, steam generators etc. with a cooled shaft or flue for the rising combustion gases. The appliances of this kind hitherto known involve the drawback that on account of the influence of the radiation of the shaft walls their temperature at the side touching the gases was lower than the dew point of the combustion gases so that the moisture of these gases condensed upon the inner wall of the shaft. Experience shows that this condensation assists to a very great extent the combustion gases in their chemical influence upon the shaft walls and is the cause of their early destruction.

It has been proposed to prevent the condensation of water by coating the cooled walls exposed to the combustion gases with a material of lesser thermal conductivity. This however involves several disadvantages; the material suitable for such coating (e. g. asbestos) has very little strength and is easily damaged for this reason. Therefore special precautions must be taken to protect it. Besides it is difficult to fasten such a coating on the walls of a liquid heater. Inasmuch as in addition to all this such a coating acts as a non-conducting material the heating effect of the cooled wall is considerably reduced.

According to the present invention, now, the condensation on the cooled walls is avoided by arranging another metal wall facing the combustion gases at a certain distance from the wall to be protected; this wall is connected with the protected wall at certain intervals by a heat conductor. The effect of this arrangement can be concluded from the following: if the wall be unprotected the heat of the combustion gases is transmitted everywhere through the wall into the liquid, i. e. it has to overcome only the comparatively small thermal resistance of the wall depending upon its thickness, so that only a small drop of temperature is caused. With the arrangement according to

my invention on the other hand the heat transmitted to the protecting wall has to be conveyed therein a considerable length of way until it is transmitted at the points where the protecting wall and the main wall are connected into the latter and from there into the liquid. For this reason, i. e. owing to the longer distance to be traversed by the heat, a greater difference in temperature is necessary, i. e. the protecting wall will be hotter than the wall to be protected. As the entire heat entering the protecting wall must flow through the comparatively small places of contact between the walls, in these places an especially powerful flow of heat results which cannot be maintained but by a greater drop in temperature, so that also in these places the temperature of the walls will be considerably higher on the side facing the gases than in cooled shaft walls directly exposed to the heating gases. Provision can be made either by experiments or calculation that the drop in temperature required for transmitting the heat from the protecting wall to the liquid becomes so high that the temperature of the protecting wall is higher than the dew point of the heating gases. Thus the protecting wall remains perfectly dry and is protected from the chemical influences of the gases. On the other hand the temperature of this protecting wall cannot become unduly high as the heat transmitted into the protecting wall is conducted through the points of connection into the protected wall and from there into the cooling medium touching it. In order to ensure an exact regulation of the temperature of the protecting wall in those places where the cooling medium still has a lower temperature, the points of contact may be arranged at a greater distance from each other, so that the way traversed by the heat in the protecting wall increases and that the difference of temperature between the latter and the cooling medium is greater than in those places where the cooling medium has a higher temperature.

As now the protected wall is not touched any more by the gases no moisture can settle on it.

In order to ensure this absolutely and to prevent the combustion gases from entering the small interstice between protecting and protected wall the arrangement may be fur-

ther improved by closing this interstice at the edges of the protecting wall.

In the drawings affixed to this specification and forming part thereof several modifications of a liquid heater embodying my invention are illustrated by way of example. In the drawings—

Fig. 1 is a vertical section following line I—I in Fig. 2,
10 Fig. 2 a horizontal section on the line II—II in Fig. 1,

Figs. 3 to 8 show various details,

Fig. 9 illustrates another modification.

The heater consists of an annular tank 15 confined by the inner wall 1 and the outer wall 2. At the lower end of this tank a burner 3 is placed. The heating gases flow at first through an empty shaft 5 formed by the lower part of the heater and then 20 enter the radiator 4 in which they lose most of their heat. They leave the heater through the top opening of the cap 6. Inside the shaft 5 at a small distance from the inner wall 1 of the tank another wall, 25 the protecting wall 7, is arranged which consists equally of metal. The protecting wall has vertical grooves 8 whose back faces are thermally connected with the cooled wall 1. The top end of wall 7 at 9 is bent back 30 in the direction of wall 1 so as to prevent the gases from entering the interstice between the walls 1 and 7.

This space may of course be closed in any other way, e. g. by inserting a cord 10 of material able to withstand the heat, as 35 shown in Fig. 3.

The construction of the connecting places between the cooled wall 1 and the protecting wall 7 can be carried out differently. 40 Instead of the vertical grooves horizontal ones might be arranged. A further modification is shown in Figs. 4 and 5. Here the protecting wall 7 has saucer-like indentations whose back faces are connected with 45 the cooled wall 1.

The projections, grooves etc. connecting both walls may of course be provided also in the cooled wall 1.

For transmitting the heat from the protecting wall 7 to wall 1 separate intermediate bodies may be arranged which are thermally connected with both walls. An example is to be seen in Fig. 6, here a third corrugated wall is inserted between 55 walls 1 and 7 transmitting the heat from wall 7 to wall 1.

The thermal connection between protecting and cooled wall can be accomplished in some way or other, such as by soldering, 60 welding or by mere pressure. A modification of the last-named type may be seen in Fig. 7; here the protecting wall 7 of a cylindrical flue is dissolved into separate segment-like parts whose ends are provided with short bends 15, which lean

against wall 1. By the spring-like action of the curved back faces of the wall parts fitted in under pressure a lasting pressure of the bends 15 against the cooled wall 1 is ensured.

Fig. 8 shows an example for the adaptation of this invention to a wall 1 which is not cooled continuously but in zones. The cooling of the wall is done by a liquid contained in pipes which are soldered upon 75 wall 1 at certain distances.

The protecting wall is in this case thus connected with wall 1 that the portions connecting both walls lie between each two cooling pipes 16. The heat entering the 80 protecting wall 7 cannot but flow in this wall to this connecting place and then through wall 1 to the connections of the pipes 16 before it reaches the liquid. Through this long wandering of the heat a 85 temperature of the protecting wall well above the dew point of the heating gases is obtained with great security.

It has further been ascertained that the condensation does not only take place in 90 the heating shafts but as well on the walls of the intrinsic heat-transmitting appliance, especially in those places where they are not covered with ribs. For this reason it is desirable to cover these parts of the wall 95 with a protecting mantle too; but its arrangement is mostly very difficult on account of the rather complicated construction of such heat-transmitting appliances.

According to the present invention those 100 parts of the heater wall, which are mostly exposed to destruction through condensation, are to be protected by shaping the radiator ribs nearest to these walls into a protecting wall so that separate protection 105 walls become superfluous.

Fig. 9 is a vertical section of a liquid heater embodying this feature. Here the heat transmitting body of a heater for liquids is arranged in the upper part of the shaft 21. The liquid which is to be heated pours into the distribution chamber 22 arranged on the one side of the shaft, is led across the stream of heating gases in 110 pipes 23, is recollected in a collection chamber 27 arranged on the other side of the funnel and is from there led to their destination. The tubes or channels 23 containing the liquid are provided with 115 ribs 24 which run in the direction of the gas current marked by arrows. According to the ordinary construction of such heat-transmitting appliances the heating gases flow through the narrow space between the end ribs 24' and 24'' and the 120 inner walls 25 and 26 of the tanks 22 and 27. As the walls 25 and 26—contrary to the channel walls 23—possess no enlarged 125 surface on the side exposed to the gases, their temperature becomes only very little 130

higher than that of the liquid so that on these walls condensation can take place, especially on wall 25 containing the cooler liquid. According to the present invention this disadvantage is avoided by shaping the ribs 24' and 24'' adjoining these walls into protecting walls. For this purpose these ribs as compared to the others, are somewhat elongated in the direction facing the current of heating gases and their ends are connected with the walls 25 and 26, so as to prevent the heating gases rising up in shaft 21 from getting into the interstices between wall 25 and rib 24' and between wall 26 and rib 24''; by this the walls 25 and 26 are protected from condensing moisture. A detrimental overheating of the ribs 24' and 24'' serving as protecting walls is prevented by their thermal connection with the channels 23 containing the liquid.

In those cases where a water-cooled shaft is used the ribs serving as a protecting mantle may extend directly into the protecting wall of the funnel shaft.

I claim:

1. In apparatus of the kind described in combination, a wall, means for cooling one side of said wall, a protective metal wall disposed near, but spaced apart from the other side of said cooled wall, heat-conductive connections between said walls and means for preventing hot gases from entering from below the space intermediate said walls.
2. In apparatus of the kind described in combination, a wall, means for cooling one side of said wall, a protective metal wall disposed near, but spaced apart from the other side of said cooled wall, metallic connections between said walls and means for

preventing hot gases from entering from below the space intermediate said walls.

3. In a liquid heater in combination, a liquid container of annular section, a protective metal wall disposed near, but spaced apart from and connected in some places to the inner wall of said container, and connections between the lower portions of said walls for preventing hot gases from entering the space intermediate said walls.

4. In apparatus of the kind described in combination, a wall, means for cooling one side of said wall, a protective metal wall disposed near, but spaced apart from the other side of said cooled wall, heat-conductive connections between said walls held in contact with the other side of said cooled wall by mere pressure and means for preventing hot gases from entering from below the space intermediate said walls.

5. In apparatus of the kind described in combination, a wall, and ribbed elements disposed at an angle to and operatively connected with said wall, means for cooling one side of said wall and said elements, the ribs adjoining said cooled wall extending along, but spaced apart from said cooling wall so as to form a protective wall.

6. In apparatus of the kind described in combination, a liquid container of annular section, a protective wall surrounded by and substantially concentric with said container, heat-conductive connections between said container and said wall and connections between the lower edges of said container and said wall for preventing hot gases from entering the space intermediate said walls.

In testimony whereof I affix my signature.

HUGO JUNKERS.
